UNITED STATES PATENT OFFICE.

THEODORE J. GARISIO, OF ALLENTOWN, PENNSYLVANIA.

LET-OFF DEVICE.

Application filed April 14, 1926. Serial No. 101,976.

My invention relates to certain improvements in mechanism used in connection with doups when making selvages intermediate the full width of the goods to make the so 5 called "split goods" of half-loom width.

These selvages are usually known as center selvages, in distinction of selvages at the edges of the fabric.

In my United States Patent No. 1,570,738, 10 dated January 26, 1926, I have shown a construction of frame carrying let-off mechanism for producing faggotting. These frames cannot readily be mounted on some of the wide goods silk looms now in use to make 15 centre selvages for the reason that there is not sufficient room between the rear rails of the loom frame and the harness, and in order to enable the device to be properly mounted on such looms it became necessary to use a 20 different or modified construction.

To this end the frame carrying the let-off mechanism shall be adjustable across the loom as well as from front to rear, and also, if desired, vertically, in accordance with the 25 disposition of the harness. The two selvage threads shall always leave a let-off frame at nearly the same point.

Referring to the drawings, in which like parts are similarly designated—

30 Figure 1 is a perspective view showing a device embodying my invention attached between the horizontal rails of the rear of a loom frame.

Fig. 2 is a rear elevation of the device. 35 In the present construction I have a frame much wider at the top than at the bottom and symmetrical with respect to a vertical, central line or axis. In this frame near the top and outer edges I place two 40 pins 34 carrying the spools 35 for the respective centre selvage forming threads α and γ which leave the frame 30 near the middle of the wider top edge. Each thread passes from its spool 35 to a pig-tail guide 42 screwed into the wooden frame 30, and thence downward to a pig-tail 29 screwed into a vertically slidable wooden weight 27 which is provided with a vertical groove. 45 A vertical staple-like wire 28 whose bent ends are driven into the frame 30 is in the groove and guides the weight 27. Each thread passes from a pig-tail 29 to a pig-tail 43 close to the middle of the frame 30 at its top.

50 Each spool has a pin 37 that strikes a

stop 40 on a pivoted hook 41 whose end lies under the guide 28.

The mechanisms are substantially duplicates, and substantially as shown in my patent above referred to, the arrangement 60 being such that the two threads α and γ leave the device from pig-tails 42 close together, and that both mechanisms are on the same face of frame 30.

Now, in order to properly position this 65 frame for the doups, I mount between the upper and lower cross rails 50 of the rear of the loom frame, a vertical bar A having end flanges B through which pass bolts C securing the bar between the rear frame 70 rails 50 of the loom frame, which rails are bored at the proper place for mounting this bar.

The bar A has one or more holes D through which may pass a clamping bolt F 75 for a bracket G of flat iron bent at a right angle. One arm of this bracket has one or more perforations H through any of which the bolt may be passed. The other arm of the bracket G lies in a transverse groove K 80 in the back of the frame 30, which groove is of slightly less depth than the thickness of the arm that lies in it.

On the back of the frame extending across the bracket arm and groove is a plate L 85 secured by bolts M passing through the frame 30 and plate L and having nuts N thereon. Washers O on the front of the frame and through which the bolts pass prevent the bolt heads from injuring the 90 wooden frame when the nuts are tightened.

By this means the frame 30 can be adjusted to any extent longitudinally of the rails, the plate L clamping the frame arm tightly to the bracket arm, this adjustment 95 being great or small within the limits of the length of the bracket arm that is parallel to the loom frame rails 50 in the directions indicated by the arrow α Figure 1. The holes H in the other arm of the bracket 100 permit adjustment of the frame 30 to the front or rear of the loom, as indicated by the arrow ν . Consequently I can adjust the frame 30 in three rectangular directions or any one of them.

The particular construction of the let-off mechanism is such that the final guides on the frame 30, for the selvage threads going to the doups, namely, pigtails 43, are close together, so that these threads can pass the 110

doups at the same location with respect to the harness of the loom.

My invention enables the use of let-off mechanism with certain types of looms with which it was either impossible or difficult to use them, decreases materially the breakage of the selvage threads x and y , facilitates superintendence by the operator, and lessens the work of the loom fixer, in case the 10 threads break and necessitate re-threading.

I claim—

1. A let-off for intermediate selvage devices comprising a frame carrying a pair of take-up devices and final thread guides adjacent one another, and means to bodily adjust the frame in three rectangular directions.

2. A let-off for intermediate selvage devices, comprising a frame carrying a pair of take-up devices and final thread guides closely arranged to one another, and means to adjust the frame in two rectangular directions.

3. A let-off for intermediate selvage devices comprising a frame having a pair of rotatable spools thereon spaced apart, a gravity take-up for each spool and arranged between them, means operated by the take-up to release the spools and a final thread

guide for the thread of each spool, said 30 guides arranged close to one another between the take-ups.

4. A let-off for centre selvage devices, comprising a frame having a transverse groove, a bracket having two arms at right angles to one another, one of said arms arranged in said groove, a clamp on said frame to clamp said arm in the groove and permit adjustment therealong, and means on the other arm to permit the bracket to 40 be adjusted longitudinally of the loom.

5. A let-off for centre selvage devices, comprising a vertical bar at the rear of the loom having bolt-holes therealong, a bracket having two arms at right angles to each 45 other, one of which arms has bolt-holes therealong, a bolt for securing said arm to said bar, in combination with a frame having a transverse groove in which the other arm of said bracket lies, a plate on 50 said frame arranged across said groove, and bolts on the frame to tighten said plate against the arm in the groove to permit the frame to be adjusted along said arm, and at least two let-off mechanisms on said frame. 55

In testimony that I claim the foregoing as my invention, I have signed my name.

THEODORE J. GARISIO.
